ORGAN CONSOLE

William Millington, Grand Rapids, Mich., and
Wilbur M. Day, Kenwood, Ohio, assignors to
The Baldwin Company, Cincinnati, Ohio, a cor-
poration of Ohio

Application July 27, 1950, Serial No. 11,432

Term of patent 14 years

(Cl. D56—2)

To all whom it may concern:

Be it known that we, William Millington and Wilbur M. Day, citizens of the United States of America, residing at Grand Rapids, in the county of Kent and State of Michigan, and at Kenwood, in the county of Hamilton and State of Ohio, respectively, have invented a new, original, and ornamental Design for an Organ Console, of which the following is a specification, reference being had to the accompanying drawing, forming a part hereof.

The figure is a perspective view of an organ console showing our design.

The dominant feature of our design resides in that portion shown in full lines on the drawing. The pedal clavier has been indicated in dotted lines with a portion near the margin broken away for convenience of illustration.

We claim:
The ornamental design for an organ console,
substantially as shown and described.

WILLIAM MILLINGTON.
WILBUR M. DAY.
